UNITED STATES PATENT OFFICE.

JOSEPH M. I. MARIN, OF JERSEY CITY, NEW JERSEY.

WEARING APPAREL.

Application filed June 2, 1926, Serial No. 113,204.

This invention relates to certain new and useful improvements in wearing apparel and more particularly to men's shirts and has for its primary object to provide a shirt 5 with reinforced portions in proximity of the waist line that are provided with button holes to receive buttons on the inner side of the waist bands of trousers whereby the lower tail end of the shirt is effectively 10 retained within the trousers to present a neat appearance and prolong the cleanliness of the shirt by causing the same to lie smoothly on the body and eliminate the unsightly appearance of bulges, wrinkles 15 and the like.

A further object of the invention is to provide a shirt of the above type having button hole slots disposed adjacent the waist line and circumferentially spaced to be engaged by buttons on the waist bands of 20 trousers, those portions of the shirt provided with the button hole slots being reinforced, either by strips sewed to the inner side of the shirt with tabs provided with 25 button hole slots stitched to the other side of the shirt, or with button hole slots formed directly in the shirt body with a reinforcing patch of the same material stitched to the shirt body inwardly of the 30 button hole slots without destroying the continuity of the design of the shirt material, for supporting the trousers in position without the necessity of providing other supporting means for the trousers, 35 such as waist belts, suspenders or the like.

With the above and other objects in view that will appear as the nature of the invention is better understood, the same consists of the novel construction, combination and 40 arrangement of parts to be hereinafter more fully described and then claimed.

In the accompanying drawings, wherein like characters designate corresponding parts throughout the several views,

45 Figure 1 is a fragmentary plan view of a portion of a shirt adjacent the waist line showing a button hole tab,

50 Figure 2 is a cross sectional view taken on line 6—6 of Fig. 1 showing the button hole slots formed directly in the shirt body with the latter reinforced by a patch displaying the same design as the shirt material,

55 Figure 3 is a detail sectional view taken on line 7—7 of Fig. 1,

Figure 4 is a vertical sectional view,

showing reinforcing strips extending from the shoulder to the waistline of the shirt and with the button hole slots formed directly in the shirt body, a pair of trousers illustrated by section being shown as buttoned to the shirt, and

Figure 5 is a detail sectional view showing a portion of a shirt and reinforcing tab stitched to the inner face thereof with button hole slots extending through both the shirt and tab.

Referring more in detail to the accompanying drawings, there is illustrated a man's shirt of the usual type comprising side front sections and a rear section, the shirt being of coat type that is buttoned lengthwise of the front sections. The present invention aiming to eliminate the necessity of wearing of a waist belt or suspenders for supporting trousers provides reinforced portions adjacent the waist line of the shirt in which button hole slots are formed to receive buttons carried by the inner side of the waist band of trousers; the tail end of the shirt being effectively retained within the trousers and prevented from rising upwardly thereof and eliminating the unsightly appearance of a bulge or overhanging fold of the shirt above the trousers, it being possible to assume any posture desired with the tail of the shirt still retained within the waist band of the trousers.

By the use of a shirt of this character, a snug fit over the shoulders and around the body of the wearer is assured and enables a longer period of cleanliness and the desired tidiness.

As shown in Figures 1 to 3, the shirt fabric 8 having the design 9 on a part thereof is longitudinally slotted at 10 to form a tab 11 that is continuous with the shirt material. An inwardly positioned patch 12 displaying the same design as the shirt fabric 8 is stitched as at 13 to the inner side of the shirt fabric inwardly of the tab 11. The tab 11 is provided with vertically spaced button hole slots 14 and the side slots 10 permit ready access to the slots to facilitate positioning of a trousers button therein.

Another form of the invention is illustrated in Figure 4 wherein the front and rear sides 15 and 16 of the shirt are provided with reinforcing strips 3^b while portions of the shirt sections 15 and 16 adjacent the waistline are directly provided with but-

ton hole slots 17, the shirt sections being slot-
ted between the stitching lines 18 above and
below the slots 17. It is to be understood
that the reinforcing strips 3^b display the
5 same design as the shirt rearwardly of the
slots 17.

As shown in Figure 9, the shirt body 20
has a tab 21 stitched to the inner side there-
of as at 22 with button hole slots 23 extend-
10 ing through the shirt body and tab.

From the above detailed description of the
invention, it is believed that the construction
and operation therof will at once be ap-
parent, and while there are herein shown
15 and described the preferred embodiments of
the invention, it is to be understood that
minor changes may be made therein without

departing from the spirit and scope of the
invention as claimed.

What I claim as new is:

As a new article of manufacture a shirt
for men's wear comprising a bosom portion,
a back and sleeves, the bosom portion formed
with a plurality of pairs of longitudinal
slits, said slits forming intervening tabs con-
tinuous of and integral with the shirt, and
with backing plies stitched to the shirt bosom
25 back of the slitted portion, the said bosom
portion being provided with button holes
between each pair of slits, for the reception
of the buttons on the waist portions of
trousers.

In testimony whereof I affix my signature.
JOSEPH M. I. MARIN.
